CLAIM

I claim the ornamental design for box, as shown and described.

DESCRIPTION

FIG. 1 is a top, front, right side perspective view of a first embodiment of the box embodying my new design;
FIG. 2 is a bottom, rear, right side perspective view thereof, the left side view being a mirror image of the right side;
FIG. 3 is a plan view thereof in an unfolded condition;
FIG. 4 is a top, front, right side perspective view of a second embodiment of the box embodying my new design;
FIG. 5 is a bottom, rear, right side perspective view of FIG. 4, the left side view being a mirror image of the right side; and,
FIG. 6 is a plan view of FIG. 4 in an unfolded condition.
